(57) CLAIM

The ornamental design for a jewelry setting, substantially as shown and described.

DESCRIPTION

FIG. 1 is a perspective view of a jewelry setting, taken from above and right;

FIG. 2 is a top view thereof,

FIG. 3 is a front view thereof; and,

FIG. 4 is a side view thereof.

The broken line showing of parts of the drawings is included for the purpose of illustrating use and environment and forms no part of the claimed design.
